(57) **CLAIM**

The ornamental design for the raindrop for a baby swing, as shown and described.

DESCRIPTION

FIG. 1 is a front view for a new design for a raindrop for a baby swing;

FIG. 2 is a rear view thereof;

FIG. 3 is a top view thereof;

FIG. 4 is a bottom view thereof;

FIG. 5 is a right side view thereof;

FIG. 6 is a left side thereof; and,

FIG. 7 is a perspective view of the raindrop for a baby swing installed.

The broken lines illustrate environmental portions of the raindrop for a baby swing.
